RAYMOND P. LANSING, OF MONTCLAIR, NEW JERSEY, ASSIGNOR TO ECLIPSE MACHINE COMPANY, OF ELMIRA HEIGHTS, NEW YORK, A CORPORATION OF NEW YORK.

ENGINE-STARTING MECHANISM.

Application filed January 18, 1928. Serial No. 247,728.

- This invention relates to engine starting apparatus, and more particularly to combined starting and ignition mechanism for internal combustion engines.
- 5 It has heretofore been proposed to employ starters of the inertia type for internal combustion engines. A starter of this character embodies, in certain instances, a small flywheel which rotates a driven member adapted to engage, but normally out of engagement with, a member provided on the engine crank shaft or an extension of the latter. In order to effectively employ a small flywheel the same must be rotated at high speed and means 10 including reduction gearing are interposed between said flywheel and the engine engaging member whereby the latter is driven at a relatively low speed. Manually operable means may be employed for bringing the flywheel to the desired speed of rotation, and in this event the gearing referred to is employed as a part of said manually operable means whereby one revolution of a member, such as a hand crank, is effective to rotate the 15 flywheel a large number of times.
- When sufficient energy has been stored in the inertia element of the starter, i. e., when the flywheel has been brought to a very high speed of rotation, the engine engaging member is quickly moved into driving engagement with the engine crank shaft member, whereby the crank shaft is rotated and the engine 20 started.
- In many instances it is desirable to supply 25 the ignition current for an internal combustion engine from a magneto that is mounted on and driven by the engine. During the starting of the engine the magneto is driven at such a low speed as to frequently be ineffective to supply the desired current. In order to overcome this difficulty it has heretofore been proposed to provide a "booster" magneto operatively connected to an engine hand turning gear. A large magneto adapted 30 to do its work at any speed was required for this purpose.

An object of the present invention is to provide novel starting and ignition mechanism for internal combustion engines which mechanism includes, in combination, a booster magneto and an inertia starter.

Another object of the invention is to provide, in combination with an inertia starter, a booster magneto adapted to be driven by 35 the flywheel of the starter.

A further object is to provide an inertia starter having suitable gearing operatively connected to the starter flywheel and to a booster magneto whereby the latter may be driven at high speed, thus permitting the use 60 of a relatively small magneto.

Another object is to provide, in combination with an inertia starter, a booster magneto adapted to be driven by the starter, the magneto being disconnected from said starter 65 during the time that energy is being stored in the flywheel of the latter.

Another object is to provide, in combination with starting mechanism of the type embodying a flywheel and a member driven 70 by the flywheel and adapted to be moved into driving engagement with the engine to be started, a magneto mounted in driving relation with the flywheel and adapted to be connected therewith by mechanism for moving 75 the engine engaging member into driving engagement with the engine.

A further object is to provide a booster magneto in combination with inertia starter mechanism and manually operable means for 80 engaging the booster magneto with the said mechanism after energy has been stored in the latter.

A still further object is to provide, in combination with an inertia starter, a booster 85 magneto mounted thereon and adapted to be drivably connected with the gearing of the starter, the driving connection being made with a part which is rotated at high speed. The above and other objects will appear more 90 fully in the detailed description.

Two embodiments of the present invention are illustrated in the accompanying drawings wherein like reference characters refer to like parts throughout the several views. 95 It is to be expressly understood, however, that the drawings are for purposes of illustration only and are not designed as a definition of the limits of the invention, reference being had for this purpose to the appended 100 claims.

In the drawings,—

Fig. 1 is an elevation in axial section illustrating one embodiment of the present invention;

Fig. 2 is a perspective view of another embodiment of the present invention; and

Fig. 3 is an elevation, in axial section, of the embodiment of the invention shown in Fig. 2.

105

110

Referring more particularly to Fig. 1, the starter comprises a housing constituted by an inner section 4, adapted to be bolted or otherwise suitably secured to the rear end of an engine crank case 5, and an outer portion 6 adapted to be secured to portions 4 by screws 7. Rotatably mounted in the outer end of housing portion 6 is a flywheel 8 which is preferably enclosed by a light cover 9 secured to said housing by means of a suitable number of screws, one of which is shown at 10. The flywheel is adapted to rotate a starter jaw 11 which is normally out of engagement with, but which is movable to engage a jaw 12 formed on the crank shaft (not shown) of the engine to be started, or on an extension of said crank shaft.

Means are provided for rotating flywheel 8 at high speed, whereby energy may be stored therein for effecting starting of the engine.

Either power or manual means may be provided for rotating the flywheel, but in the illustrated embodiment of the invention said means are of the manually operable type and include a shaft 13 rotatably mounted in housing portion 6, as by means of suitable bearings 14. One end of shaft 13 projects exteriorly of the housing and is provided with a pin 15, whereby said shaft may be rotated by a suitable hand crank (not shown). Mounted on the inner end of shaft 13 is a bevel gear 16 which meshes with a bevel gear 17 rigidly secured to the outer end of a rotatably mounted sleeve 18. The inner end of sleeve 18 is drivably attached in any suitable manner to the closed end 19 of a driving barrel 20 which is rotatably mounted in housing portion 4 by means of ball bearings 21. Extending outwardly from the closed end of barrel 20 are three tubular sleeves 22, one of which is shown in section. Each of these sleeves, which are spaced apart at intervals of 120° around the end of the barrel, is pressed into a counterbore formed in barrel end 19 and is formed integrally with a retaining ring 23. Screws 24 pass through the sleeves and are threaded into the barrel. Ball bearings 25, which are mounted on sleeves 22, rotatably support three planetary gears 26, one of which is shown in section.

The planetary gears 26 mesh with an internal gear 27 which is rigidly mounted within housing portion 4 as by means of studs 28. The planetary gears also mesh with a sun gear 29 that is rotatably mounted on sleeve 18. A gear 30, which is preferably formed integrally with sun gear 29, is also rotatably mounted on sleeve 18 and is provided with an inner series of teeth to form an internal gear 31 which meshes with a pinion 32. Gear 30 is also provided on the periphery thereof with a series of teeth for a purpose to be described hereafter. Pinion 31 is preferably attached in any suitable manner to a bell-shaped member 32 which is rotatably mounted in housing

portion 6 and is provided on its flanged end with a series of teeth constituting a spur gear 33 that meshes with a pinion 34 rigidly carried on the inner end of a hollow shaft 35 that is keyed to the hub of flywheel 8. As shown, flywheel 8 is rotatably mounted by ball bearings 36 positioned in a hub 37 that is formed integrally with housing portion 6. Motion transmitting means which include a yielding driving connection are interposed between barrel 20 and starter jaw 8. In the illustrated embodiment the yielding driving connection is constituted by a multiple disk clutch, certain of the clutch disks 38 being splined to the inner surface of barrel 20, adjacent the closed end of the same. In inter-leaving relation with disks 38 are the remaining clutch disks 39 which are splined at their inner peripheries to the outer surface of an interiorly threaded nut 40. Suitable means such as springs 41 and an adjusting nut 42, which latter is threaded into the open end of drum 20, are provided for adjusting the frictional engagement of the disks of the clutch.

Mounted for longitudinal and rotary movement within nut 40 is a threaded shaft 43 which carries a nut 44 that acts as a stop to limit the outward movement of shaft 43 relative to nut 40. The outer end of shaft 43 is longitudinally splined to receive the splined portion 11 of starter jaw 11. Interposed between the inner face of the hub portion of jaw 11 and the adjacent recessed end of shaft 43 is a coil spring 45 which surrounds a rod 46. The spring 45 yieldingly resists movement of jaw 11 towards shaft 43. Rod 46 is concentrically disposed relative to starter jaw 11, shaft 43 and sleeve 18, and slidably extends through these elements, the outer end of said rod terminating adjacent the center of bevel gear 16. The inner or engine end of rod 46 is threaded to receive a nut 47 which abuts against the outer face of the hub portion of jaw 11 and maintains the latter in operative relation with said rod and shaft 43. Intermediate its ends, rod 46 is provided with a shoulder 46a which is normally in abutting engagement with the outer end of threaded shaft 43. Pivoted connected to the outer extremity of rod 46 is a lever arm 48 which is rigidly attached to a rock shaft 49 that extends through housing portion 6 and carries on its outer end a bell crank lever 50. Surrounding rock shaft 49 is a coil spring 51, one end of which is secured to lever arm 48 and the other end of which is anchored to the housing. Rock shaft 49, bell crank lever 50 and spring 51 are laterally spaced from the longitudinal axis of the starter mechanism and are preferably mounted in the half of said mechanism not illustrated. Accordingly, these elements are shown in dotted lines.

A booster magneto 52 is rigidly secured in

any suitable manner to the housing portion 6 of the starter, and means are provided for driving the magneto armature from flywheel 8. For this purpose housing portion 6 is 5 provided with a projecting boss 6^a which encloses a spur gear 53 that meshes with the outer teeth of gear 30. Spur gear 53 is keyed to a short shaft 54 provided with jaw teeth 55 which are permanently meshed with cor- 10 responding jaw teeth formed on a coupling 56 that is keyed to the tapered end of the armature shaft 57. The outer periphery of the hub of gear 53 rotatably engages a bushing 58 which is pressed into a hub 59 formed 15 in the housing boss 6^a and the reduced end 54^a of shaft 54 is suitably journaled in a hub 60 formed in housing portion 4.

In operation, shaft 13 is rotated by means 20 of the hand crank (not shown). This movement is transmitted through bevel gears 16, 17, sleeve 18, drum 20, planetary gears 26, sun gear 29, gear 30, pinion 31, gear 33 and pinion 34 to shaft 35 whereby flywheel 8 is rotated at high speed. At this time jaw 11, 25 threaded shaft 43, nut 40 and barrel 20 rotate as a unit and the armature shaft 57 is also rotated by means of gears 30 and 53.

When sufficient energy has been stored in flywheel 8 no further manual effort is exerted on shaft 13. The operator now rotates 30 bell crank lever 50 in such a direction that rock shaft 49 and lever arm 48 move rod 46 to the left against the tension of spring 51. The shoulder on rod 46 moves shaft 43 and 35 spring 45 to the left relative to nut 40, whereupon starter jaw 11 is yieldingly moved into meshing engagement with jaw 12 on the engine crank shaft and the energy of flywheel 8 is effective to rotate said crank shaft and 40 start the engine. Due to the gearing connection between the flywheel and armature shaft 57, said flywheel rotates the shaft at a high speed and current is supplied by the magneto 52 to the engine. Since the speed of rotation 45 of the armature shaft 57 is very high a small magneto can supply the necessary ignition current for the engine.

As soon as the engine starts under its own power and the speed of rotation of jaw 12 50 is greater than the speed of rotation of jaw 11, the tendency for the latter jaw to be driven and the threaded connection between shaft 43 and nut 40 results in these parts being returned to normal position, if bell crank lever 55 50 has been released and spring 51 has returned rod 46 to normal position. In the event that rod 46 is held in meshing position after the engine starts under its own power no damage will result because the inclined surfaces of the teeth of jaws 11 and 12 60 are effective to force jaw 11 to the right against the tension of spring 45. After the engine starts under its own power the ignition current is supplied by the engine driven magneto and the starter parts come to rest. 65

Due to the train of gearing employed and the necessity for rotating flywheel 8 at a very high speed relative to shaft 13, considerable effort is required on the part of the operator to bring flywheel 8 up to the desired speed. The permanent driving connection to the magneto armature shaft adds to the amount of torque required to rotate flywheel 8. Moreover, during the time that energy is being stored in the flywheel the magneto is not supplying current to the engine. In certain instances it is therefore desirable 70 to provide means whereby the magneto is drivably disconnected from the starting mechanism during the time the energy is being stored in the flywheel, said means being so constructed that the magneto may be drivably connected with said flywheel at the time that the energy of said flywheel is rendered effective to rotate the engine crank shaft. 75

In Figs. 2 and 3 there is illustrated an embodiment of the invention wherein the flywheel is adapted to be drivably connected to the magneto 52 at the instant that jaw 11 is moved into engine engaging position. The 80 starter elements included within housing portions 4 and 6 and the magneto, are similar to those described above. Mounted within a projecting boss 6^b formed on housing portion 6 is a spur gear 61 having a hub 62 which 85 runs in a bronze bushing 63 that is pressed into a hub 64 formed in the boss 6^b. A lock ring 65 is preferably provided on hub 62 to prevent endwise movement of gear 61. As in the previous embodiment the armature 90 shaft 57 has secured thereto, in any suitable manner, a coupling 67 provided with jaw teeth that are permanently in mesh with corresponding teeth formed on a short shaft 67. A bushing (not shown) may be interposed between the enlarged portion of shaft 67 and the bore of hub 62. The smaller end of shaft 67 is suitably journaled in a hub 68 95 formed in housing portion 4.

A circular series of teeth 69 which constitutes one-half of a toothed clutch is secured to, or suitably formed on, one face of the gear 61. Mounted on the reduced portion 67^a of the short shaft 67 is a disk 70 provided on one face thereof with a circular series of teeth 115 adapted to engage teeth 69. If desired, the disk 70 may have threaded engagement with portion 67^a of the short shaft but in the illustrated embodiment said reduced portion is square in cross section and disk 70 is mounted 120 on said squared portion for movement longitudinally thereof and for rotation therewith.

Means are provided for normally holding disk 70 out of driving engagement with gear 61, said means being also adapted to move the disk into driving engagement with gear 61 when the flywheel 8 has been brought to the proper speed of rotation, whereby the magneto armature will be driven by the flywheel. In the form shown said means comprises a 125 130

link 71 which is pivotally connected to one arm of the bell crank lever 50. The opposite end of link 71 is bent upwardly as at 71^a to receive an eye formed on the end of an L-shaped arm 72. The other end of arm 72 is rigidly attached in any suitable manner to a rock shaft 73 mounted in the upper part of the housing portion 4. A shifting fork 74 which is rigidly attached to shaft 73 extends 10 into operative engagement with the hub of disk 70.

In operation, the flywheel is manually rotated in a manner previously described. Simultaneously, gear 30 rotates gear 61 which 15 now constitutes an idler. No motion is transmitted at this time to the armature shaft of magneto 52. When sufficient energy has been stored in the flywheel 8 the operator exerts a force on bell crank lever 50 to rotate it in 20 an anti-clockwise direction, as viewed in Fig. 2. This movement of the bell crank lever is transmitted through rod 46 to move the starter jaw 11 into driving engagement with the engine shaft in a manner previously 25 described. Simultaneously with the movement of meshing rod 46, the bell crank lever acts through link 71, L-shaped arm 72, shaft 73 and fork 74 to move toothed disk 70 to the right, as viewed in Fig. 3 and into meshing 30 engagement with the teeth 69.

The flywheel now rotates armature shaft 57 through gear 61, disk 70 and shaft 67, and the booster magneto which is driven at high speed is rendered effective to supply the ignition 35 current for starting. As soon as the engine starts under its own power, starter jaw 11 is moved out of driving engagement with the jaw 12 in a manner previously described and simultaneously spring 51 returns disk 70 40 to normal disengaged position.

There is thus provided means whereby a booster magneto is adapted to be drivably connected with the flywheel of an inertia starter. Since the booster magneto is driven 45 at a very high speed by the flywheel, a small, light magneto may be employed. The device is extremely compact and may be readily installed on or removed from an engine. Due to the simple construction and light weight of 50 the apparatus it is particularly adapted for use with aeroplane engines, but is not limited to such use. For purposes of description there is illustrated and described herein a particular starter construction, but the present invention is not limited to the form of 55 starter shown. Power means such as an electric motor may be employed for rotating flywheel 8 is desired, or both manual and power means may be provided for this purpose. If it is desired to provide means whereby the magneto armature will not be driven 60 during the interval that energy is being stored in the flywheel, the apparatus provides common means for simultaneously moving 65 the starter jaw into driving engagement with

the engine and for clutching the magneto armature shaft to the reduction gearing. Practically no weight is added to the starter structure except that of a small magneto, since the reduction gearing of the starter is employed for rotating the armature shaft at high speed.

Reference has been made in several instances to the fact that the parts are so arranged as to permit rotation of the armature shaft at high speed. It is to be expressly understood, however, that the various parts, including the gearing, may be modified in any suitable manner to secure any desired speed of rotation of the armature shaft, and changes 80 may be made in the size and type of magneto employed to conform with such speed.

Various changes may be made in the details of construction of the apparatus and the arrangements of parts. Reference will therefore be had to the appended claims for a definition of the limits of the invention.

What is claimed is:—

1. In starting apparatus of the class described, a driven member adapted for engagement with a member of an engine to be started, an inertia driving member therefor, and a magneto mounted in driving relation with the inertia member.

2. In starting apparatus of the class described, a driven member, an inertia driving member therefor, means including gearing for imparting the energy of the inertia member to said driven member, and a booster magneto adapted to be driven by said inertia member 100 through said gearing.

3. In starting apparatus of the class described, a driven member movable into operative engagement with an engine to be started, a rotatable, inertia driving member therefor, means for imparting the rotation of the inertia member to said driven member, a magneto adapted to be driven by said inertia member, and means operatively connected to said first named means and said magneto for drivably connecting the latter with the inertia member.

4. In starting apparatus of the class described, a driven member movable into operative engagement with an engine to be started, 115 a flywheel for driving said member, a magneto, means including gearing operatively connected to said driven member, magneto and flywheel, and manually operable means for rotating said flywheel at high speed.

5. In starting apparatus of the class described, a driven member movable into operative engagement with an engine to be started, an inertia driving member therefor, a magneto, gearing means operatively connected to 125 said magneto and inertia member, and manually operable means for actuating said gearing means.

6. In starting apparatus of the class described, a driven member, an inertia driving 130

- member, a magneto, gearing means for transmitting motion from the inertia member to the driven member and magneto, and manually operable means for storing energy in said inertia member, said manually operable means including said gearing means.
7. In starting apparatus of the class described, a driven member, an inertia driving member therefor, a magneto, and common means operatively connected to said flywheel for rotating the magneto and driven member.
8. In combination with an inertia starter for an internal combustion engine, said starter including a driven member adapted to engage a member of the engine to be started, a magneto adapted to be driven by said starter, and common means for establishing a driving connection between said starter and magneto and for moving said driven member into engagement with said engine member.
9. In combination with starting mechanism for an internal combustion engine, said mechanism including a driven member adapted to be engaged with a member of the engine to be started, a magneto for supplying ignition current to the engine during the starting operation only, means for moving said driven member into engagement with the engine member, and means actuated by said first named means for establishing a driving connection between said starting mechanism and said magneto.
10. In combination with engine starting mechanism including a driven member adapted to be moved into engagement with a member of the engine to be started, a magneto for supplying ignition current to said engine, said magneto being mounted on said starting mechanism, and common means for moving said driven member into engagement with said engine member and for establishing a driving connection between said starting mechanism and magneto.
11. In combination with engine starting mechanism including a driven member adapted to be moved into operative engagement with the engine to be started, a booster magneto adapted to be driven by said mechanism, manually operable means for moving said driven member into engagement with said engine member, and means actuated by said manually operable means for operatively connecting said booster magneto and starting mechanism.
12. In combination, an engine starter including a flywheel and a driven member adapted to be moved into engagement with a member of an engine to be started, a magneto adapted to be driven by, but normally out of driven engagement with, said flywheel, means for moving said driven member into engagement with said engine member, means for operatively connecting said flywheel and magneto, and means for simultaneously actuating said first and second named means.
13. In combination, an engine starter including a driven member adapted to be moved into engagement with a member of an engine to be started and a flywheel for rotating said driven member, a magneto for supplying ignition current to the engine during the starting operation, motion transmitting means interposed between said flywheel and magneto, and means for simultaneously moving said driven member into engagement with said engine member and for rendering said motion transmitting means operative.
14. In combination with an engine starter of the inertia type, a booster magneto mounted on said starter, means operatively connected to said starter for driving the armature shaft of said magneto at high speed, and movable means for operatively connecting said first named means with said armature shaft.
15. In combination with an engine starter of the inertia type, a booster magneto mounted on said starter, means including normally disengaged members for operatively connecting said magneto and starter, and means for moving said members into driving engagement whereby said magneto is driven at high speed.
16. In combination with engine starting mechanism, a magneto adapted to supply ignition current to an engine to be started, means operatively associated with said mechanism and magneto whereby the latter is adapted to be driven by the former, said means including a pair of toothed members that are normally disengaged, and means for moving said toothed members into driving engagement.
17. In combination with an engine starter including a flywheel and means for rotating said flywheel, means for supplying ignition current to an engine to be started, means including gearing adapted to be driven by said flywheel, and manually operable means for establishing a driving connection between said gearing and said current supplying means, said manual means being adapted to be actuated while the flywheel is rotating at high speed.
18. In combination with an engine starter including a flywheel and means for rotating said flywheel, a magneto having an armature shaft adapted to be rotated at high speed by said flywheel, means including normally disengaged clutch elements for imparting the rotation of said flywheel to said shaft, and means operable during the rotation of the flywheel for engaging said clutch elements.
19. In combination with an engine starter embodying a flywheel and means for rotating said flywheel, a booster magneto, means for driving said magneto including a slidable clutch member, and means for moving said clutch member into driving engagement during high speed rotation of said flywheel.
20. In starting apparatus of the class de-

- scribed, a driven member movable into operative engagement with an engine to be started, a flywheel for driving said member, a magneto, means including gearing operatively connected to said driven member, magneto and flywheel, and means for rotating said flywheel at high speed to store energy therein.
21. In starting apparatus of the class described, a driven member movable into operative engagement with a member of an engine to be started, an inertia driving member for the driven member, a magneto, gearing means operatively connected to said magneto and inertia driving member, and means for actuating said gearing means whereby energy is stored in the inertia member.
22. In starting apparatus of the class described, a driven member, an inertia driving member, a magneto, means for transmitting motion from the inertia member to the driven member and to the magneto, and means for storing energy in said inertia member, said last named means including said first named means.
23. In combination with engine starting mechanism including a driven member adapted to be moved into operative engagement with a member of an engine to be started, a booster magneto adapted to be driven by said mechanism, means for moving said driven member into engagement with said engine member, and means actuated by said first named means for drivably connecting the booster magneto with said starting mechanism.
24. In combination, an engine starter including a flywheel and a driven member adapted to be moved into engagement with a member of an engine to be started, a magneto adapted to be driven by, but normally out of driving engagement with, said flywheel, means for moving said driven member into engagement with the engine member, and means for operatively connecting said flywheel and magneto.

In testimony whereof I have signed this last named means including said first named specification.

RAYMOND P. LANSING.
